UNITED STATES PATENT OFFICE.

HARRY E. MENG, OF OAK PARK, ILLINOIS, ASSIGNOR TO W. D. ALLEN MANUFACTURING COMPANY, OF CHICAGO, ILLINOIS, A CORPORATION.

HOSE-NOZZLE.

1,401,425.

Specification of Letters Patent. Patented Dec. 27, 1921.

Application filed April 5, 1920. Serial No. 371,204.

To all whom it may concern:

Be it known that I, HARRY E. MENG, a citizen of the United States, and a resident of Oak Park, in the county of Cook and

5 State of Illinois, have invented certain new and useful Improvements in Hose-Nozzles, of which I do declare the following to be a full and exact description, reference being had to the accompanying drawing, forming 10 a part of this specification.

The present invention has relation to an improvement in that class of hose nozzles wherein provision is made so that the water can be caused to issue from the nozzle either 15 in the form of a spray or as a solid stream, an example of this type of hose nozzle being set forth in Patent No. 1,014,386, granted to W. D. Allen Manufacturing Company as assignee of Henry Gibbs January 9, 1912.

20 The present invention consists in the features of novelty hereinafter described, illustrated in the accompanying drawing and particularly pointed out in the claims at the end of this specification.

25 Figure 1 is a view in central longitudinal section (parts being shown in elevation) of a hose nozzle embodying my invention. Fig. 2 is a detail view in central section through the hollow body portion of the nozzle. Fig.

30 3 is a detail view in elevation of the lower or spindle portion of the nozzle. Fig. 4 is a view in central longitudinal section (similar to Fig. 1) but showing the spindle in section and showing the parts in a position different from that illustrated in Fig. 1. Fig. 5 is a view in cross section on line 35 5-5 of Fig. 1.

In the drawing, A designates the hollow body portion of the nozzle and B denotes 40 the lower or spindle portion of the nozzle. The body A is provided at one end with a discharge orifice 7 through which the water will issue from the nozzle. Upon its interior, the body A of the nozzle is formed with a contracted portion 8, preferably about 45 its center, this contracted portion being provided with screw threads 9. As shown, the portion 8 of the nozzle body A is provided with straight channels 10 diametrically dis-

50 posed (although a single straight channel may be used if desired), the upper portions of the channels 10 leading through the shorter interiorly threaded portion 9 of the body A. Communicating with these 55 straight channels 10 are the inclined chan-

nels 11 also formed in the portion 8 of the nozzle body A, these inclined channels communicating with the straight channels 10. Those portions of the inclined channels 11 farthest from the straight channels 10 are 60 preferably enlarged as at 12 (see Fig. 2). The lower portions of the channels 10 and 11 terminate at a distance above the screw threads 9 upon the interior of the body A. The portions 12 at the ends of the inclined 65 channels 11 are diametrically disposed, as shown in Fig. 5 of the drawing. Beneath the threaded portion 9 of the nozzle body A is an inclined valve seat 13, the purpose of which will presently more fully appear. 70

The spindle or lower portion B extends within the body portion A and at its upper end the spindle B is formed with an extension b having exterior screw threads 14 adapted to engage with the interiorly threaded portion 9 of the nozzle body A. The extension b is formed with one or more water passages 15 which are adapted, as the spindle B is turned, to be brought opposite either the straight channels 10 or the inclined channels 11 of the body portion A, according as it is desired to cause the nozzle to throw a solid stream or a spray. As shown, the passages 15 are diametrically disposed and terminate below the upper threaded portion 85 14 of the spindle B.

The lower portion of the spindle B is shown as provided with an interiorly threaded portion b' adapted to engage the coupling at the end of a section of hose, in the usual 90 manner, and that part of the spindle above the threaded portion b' is formed with a chamber 16 for the passage of water. The wall of the spindle B about the chamber 16 is preferably formed with annular ribs 95 17 and 18 between which is interposed a leather or similar packing 19, and the spindle is preferably held in position within the body A of the nozzle by a skirt or flange 20 that is turned inwardly from the lower 100 end of the body portion A, as shown in Figs. 1 and 4 of the drawing.

Above the chamber 16 of the spindle B one or more ports or passageways 22 lead from the chamber 16 to the exterior of the 105 spindle B, as clearly shown in Figs. 1 and 4 of the drawings, these ports or passageways 22 being preferably arranged beneath the channels 15. The portion 24 of the spindle B at the base of the extension b forms a 110

valve adapted to coöperate with the valve seat 13 when the passage of water through the nozzle is to be entirely cut off.

From the foregoing description, the operation of my improved hose nozzle will be seen to be as follows: When the parts are in the position shown in Fig. 1 of the drawing, water will pass through the chamber 16 of the spindle B, thence through the ports 10 or passageways 22 into the chambered portion of the body A around the lower part of the extension b, and will pass thence by the channels 15 and the straight channels 10 into the chambered upper part of the body A and thence through the discharge orifice 7, issuing from the nozzle as a straight stream. When it is desired to cause the water to issue from the nozzle in the form of a spray, the body A will be partially turned until the 15 inclined channels 11 upon the interior of the body A are brought opposite the channels 15 in the upper portion of the spindle B. The water will then pass from the channels 15 into the inclined channels 11 which will 20 impart to the stream a swirling motion, and thence through the upper ends of the straight channels 10, through the chambered upper portion of the nozzle A and through the discharge orifice 7. The character 25 of the spray can be varied,—that is to say, a finer or a coarser spray can be produced by varying the position of the channels 15 with respect to the inclined channels 11. When the upper portion A of the nozzle 30 is turned until the upper end of the portion 24 of the spindle B engages the inclined valve seat 13, the passage of water through the nozzle will be completely shut off.

The details of construction above set forth 40 may be varied widely without departing from the spirit of the invention and features of the invention may be employed without its adoption as an entirety.

Having thus described my invention, what 45 I claim as new and desire to secure by Letters Patent is:—

1. A hose nozzle comprising a hollow body provided with a discharge orifice at one end and having its interior so channeled as to cause the water directed therethrough to pass from said orifice either as a straight stream or as a spray and having a valve seat, and a chambered inner member or spindle provided with a valve and arranged 50 revolvably and axially movable within said body and adapted to direct the water to different parts of said channeled body and to shut off the flow of water through said body.

2. A hose nozzle comprising a hollow interiorly threaded body provided with a discharge orifice at one end and having upon its interior straight and inclined water channels; and a chambered spindle extending within and threaded to engage said body, 55 said spindle being formed with a port lead-

ing from the upper part of its chamber and provided above said port with a water passage adapted to be brought opposite either said straight or said inclined channel.

3. A hose nozzle comprising a hollow interiorly threaded body provided with a discharge orifice at one end and having its interior channeled to cause the water directed therethrough to pass from said orifice either as a straight stream or a spray, the interior of said body being provided with a valve seat adjacent the threaded portion of said body; and a revoluble inner member or spindle threaded to engage said body, said spindle being formed with one or more water passages adapted to be brought opposite different parts of the channeled body and being provided with a valve adapted to coöperate with said valve seat. 70

4. A hose nozzle comprising a hollow interiorly threaded body provided with a discharge orifice at one end and provided upon its interior with channels adapted to cause the water directed therethrough to pass from said orifice either as a straight stream or as a spray, the interior of said body being provided below said channels with a valve seat; and a revoluble chambered inner member or spindle threaded to engage said body, said spindle being formed with water passages adapted to be brought opposite different parts of the channels in said body and being provided between its outer end and its chambered portion with a valve adapted to coöperate with said valve seat. 75

5. A hose nozzle comprising a hollow interiorly threaded body provided with a discharge orifice at one end and having upon its interior straight and inclined water channels and a valve seat; and a chambered spindle extending within and threaded to engage said body, said spindle being formed with a port leading from the upper part of its chamber and provided above said port with a water passage adapted to be brought opposite either said straight or said inclined channel, said spindle being provided between said port and said water passage with a valve to engage the valve seat of said body. 80

6. A hose nozzle comprising a hollow interiorly threaded body provided with a discharge orifice at one end and having upon its interior straight and inclined water channels, said straight channels opening through said threaded portion of the body; and a chambered spindle extending within and threaded to engage said body, said spindle being formed with a port leading from the upper part of its chamber and provided above said port with a water passage adapted to be brought opposite either said straight or said inclined channel. 85

7. A hose nozzle comprising a hollow body provided upon its interior with an interiorly threaded contracted portion, said contracted 90

portion forming a valve seat and having parts of said threaded portion cut away to form water channels adapted to cause the water to pass from said orifice either as a straight stream or as a spray; and a chambered inner member or spindle extending within and threaded to engage said body,

said spindle being formed with a valve to engage said valve seat and with a port leading from the upper part of its chamber and 10 provided above said port with a water passage adapted to be brought opposite different parts of the channels of said body.

HARRY E. MENG.
